(57) **CLAIM**

The ornamental design for a beverage container, as shown
and described.

DESCRIPTION

FIG. 1 is a top perspective view of a beverage container,
showing my new design;

FIG. 2 is a bottom perspective view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top plan view thereof; and,

FIG. 8 is a bottom plan view thereof.

The broken lines showing portion(s) of the beverage
container are for the purpose of illustrating environmental
structure only and forms no part of the claimed design.

1 Claim, 7 Drawing Sheets
